(57) **CLAIM**

The ornamental design for a vehicle chassis, as shown and described.

DESCRIPTION

FIG. 1 is a top plan view of a vehicle chassis showing my new design, as shown in one environment being in broken lines, the environment not being a part of the disclosed and claimed design;

FIG. 2 is a rear elevational view thereof;

FIG. 3 is a right side elevational view thereof;

FIG. 4 is a left side elevational view thereof; and,

FIG. 5 is a front elevational view thereof.
